[57] CLAIM

The ornamental design for a top, front, rear and sides of a
“battery charger”, as shown and described.

DESCRIPTION

FIG. 1 is a top, front, and left side perspective view of the
top, front, rear and sides of a battery charger showing our
new design in which the top, inner, left surface has the same
appearance as the top inner right surface;
FIG. 2 is a right side elevational view thereof; and,
FIG. 3 is a rear side elevational view thereof.
